UNITED STATES PATENT OFFICE.

CHARLES A. CAMPBELL, OF NEW YORK, N. Y.

GAS-BURNER.

SPECIFICATION forming part of Letters Patent No. 758,411, dated April 26, 1904.

Application filed October 6, 1903. Serial No. 175,957. (No model.)

To all whom it may concern:

Be it known that I, CHARLES A. CAMPBELL, a citizen of the United States, and a resident of the city of New York, borough of Brooklyn, 5 in the county of Kings and State of New York, have invented a new and Improved Gas-Burner, of which the following is a full, clear, and exact description.

This invention relates to an incandescent 10 gas-burner, and the prime object of the invention is to so control the circulation of air past the mantle as to produce the best possible results from the amount of gas consumed. The invention relates to that class of gas-burners 15 in which a mixture of air and gas is burned within the mantle, and the burner is provided with orifices to allow a current of air to pass up through the chimney outside of the mantle. I attain the object in view with a burner of 20 this class, and in so doing I provide a cup which encircles the burner-tube and the lower portion of the mantle, thus preventing any air from entering the mantle excepting that which is mixed with the gas to promote combustion. At the same time a strong current 25 of air is allowed to pass up around the burner-tube outside the mantle, so as to cool the tube and increase the intensity of the light given off from the mantle.

30 This specification is an exact description of one example of my invention, while the claims define the actual scope thereof.

Reference is to be had to the accompanying drawing, forming a part of this specification, 35 which represents a vertical section of the invention.

a indicates the nipple and valve, which are connected with the gas-supply.

b indicates the mixer, *c* the burner-tube, and 40 *d* the neck thereof.

e indicates a foraminated support for the chimney *f*, which latter is provided at its lower portion with air-inlet orifices *f'*, and *g* indicates the fastening means for the rod *h*, 45 which supports the mantle *i*.

All of the above-described parts are well known in the art and may be of the usual or any preferred construction.

50 My improvement lies in the cup or shield *k*, which surrounds the burner-tube *c* and is sup-

ported thereon, the contracted lower portion of the cup snugly engaging the tube and the upper end of the tube flaring out toward the orifices *f'*. This cup *k* incloses the lower end of the mantle *i* and protects the burner-tube 55 from the cooling influences of the air rising through the foraminated support *e*, and it also prevents this air from entering the space within the mantle.

In the operation of the burner the gas and 60 air from the tube *c* are burned in the mantle *i* in the usual manner. A current of air rises through the foraminated support *e* and is thrown outward by the flared outer portion of the cup *k*. This current of air meets the 65 currents entering the chimney through the orifices *f'* in the base of the chimney *f*. These converging currents of air strike each other and rise around the inner sides of the chimney in the form of a continuous steady current. By means of this improvement I am 70 enabled greatly to increase the efficiency of the burner and to produce with a given quantity of gas a stronger light than heretofore.

Various changes in the form, proportions, 75 and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. The combination with a gas-burner, comprising a burner-tube, a mantle and its support, an orificed chimney, and an orificed 85 chimney-support, of a hood or cup inclosing the burner-tube and extending upward to inclose the lower portion of the mantle, said hood or cup being flared outward toward the orifices in the chimney, said chimney being suddenly enlarged opposite said flared top of the cup, the orifices in the chimney being located at that point, for the purpose specified.

2. In a gas-burner, a mixing-chamber having air and gas inlets at its lower portion, a contracted or neck portion above said mixing-chamber, a burner-tube surmounting said neck portion, a shield surrounding said burner-tube, said shield being contracted at its bottom into peripheral engagement with the 95

lower end of said burner-tube to form a chamber with a closed bottom around said tube, said shield extending upwardly in parallelism with the burner-tube to a point near its top 5 and terminating in an annular outward flare, a foraminated chimney-support surrounding said neck portion, and a chimney upon said support, said chimney being provided with a contracted portion at its lower end having 10 vertical walls extending upwardly to the flared portion at the top of said shield, the chimney having a right-angled offset at that point to prevent a contraction of the air-passage oppo-

site said flared portion of the shield, the chimney being also provided with air-inlet openings at the lower end of its enlarged portion, and the lower portion of the mantle being surrounded by the flared portion of the shield. 15

In testimony whereof I have signed my name 20 to this specification in the presence of two subscribing witnesses.

CHARLES A. CAMPBELL.
